UNITED STATES PATENT OFFICE.

ROBERT W. COFFEE, OF BEDFORD CITY, VIRGINIA.

MACHINE FOR MANIPULATING FINE-CUT TOBACCO.

SPECIFICATION forming part of Letters Patent No. 436,032, dated September 9, 1890.

Application filed March 18, 1890. Serial No. 344,389. (No model.)

To all whom it may concern:

Be it known that I, ROBERT W. COFFEE, a citizen of the United States, residing at Bedford City, in the county of Bedford and State of Virginia, have invented a new and useful Machine for Manipulating Fine-Cut Tobacco and like Material, of which the following is a specification.

This invention relates to machines for manipulating fine-cut tobacco and the like and for the purpose of extracting excessive moisture from the same by the combined action of currents of hot and cold air; and it consists in the details of construction of said machine, which will be hereinafter fully described, and particularly pointed out in the claims.

Heretofore in the process of extracting excessive moisture from fine-cut tobacco and analogous material it was usual to manipulate the material twice, either in two different machines or twice in succession by the same machine, the purpose of the first manipulation being to subject the material to the action of hot air, whereby the excessive moisture shall be vaporized and drawn off, and the purpose of the second manipulation being to subject the material to the action of comparatively cold air for the purpose of reducing the temperature and preventing the material from clogging and matting. This has been objectionable for the obvious reason that it involves the duplicate handling of the material.

By my present invention I aim to construct a machine in which by a single manipulation the material shall be subjected to the successive actions of currents of hot and cold air, thereby dispensing with one manipulation, and consequently effecting a reduction in the cost of the finished products.

In the drawings hereto annexed, Figure 1 is a perspective view of a machine embodying my improvements, parts of the casing of the same having been broken away for the purpose of exposing the interior construction. Fig. 2 is a longitudinal vertical sectional view of the same. Fig. 3 is a side elevation with parts of the casing broken away. Fig. 4 is a vertical transverse sectional view taken on the line $\alpha\alpha$ in Fig. 3. Fig. 5 is an end elevation. Fig. 6 is a perspective detail view of a portion of the revolving cylinder.

Like numerals of reference indicate like parts in all the figures of the drawings.

1 designates a suitable base, having a series of brackets or uprights 2 2, affording bearings for the rollers 3 3, that serve to support a revoluble hollow cylinder or drum 4, which is provided with annular bands or tires 5, having flanges 6, that engage annular grooves 7 in the rollers 3, so as to keep the said cylinder in its proper position. The said cylinder is slightly inclined in a downward direction from its feed to its discharge end, as will be clearly seen in Figs. 2 and 3 of the drawings, it being supported in this position by means of the supporting-rollers 3, the bearings of which are slightly raised at one end. The flanges 6, engaging the grooves 7 in said rollers, serve to prevent the cylinder from sliding longitudinally thereon. The feed end 8 of the cylinder 4 is closed, with the exception of a central opening 9, through which extends a feed-tube 10, which is supported upon a bracket 11, suitably mounted upon the base. The said feed-opening of the cylinder is also provided with a spur-wheel 12, or a circumferential series of teeth meshing with a pinion 13, mounted upon a short shaft 14, which is journaled in suitable bearings, and which is provided with fixed and loose pulleys designated, respectively, by 15 and 16, the form of which is adapted to receive motion by an ordinary power-belt from driving machinery of any kind.

The revolving cylinder 4 is inclosed by a casing 17, one end of which practically forms a bearing for the feed end of the cylinder and the other end of which is provided with a cap 18 to close the discharge end of the cylinder. Said cap is provided with a discharge-opening, which is covered by a hood 19, and through which the contents of the cylinder may eventually escape. The cylinder 4, which is constructed of sheet metal, is provided with a series of longitudinal slots 95 or openings 20, extending through its entire length and dividing it into a series of segments 21, which are connected by means of what may be termed the "buckets" 22, which are secured interiorly to the said cylinder by 100 means of flanges 23, which are secured in any suitable manner to the segments or sections

thereof. Each of the said buckets is composed of a strip of sheetmetal of suitable dimensions, which is bent so as to form a flat side 24 and a curved side 25, and the edges of which are 5 provided with the flanges 23, above referred to. The flat sides 24 of the said buckets, which are the front sides when the direction of rotation of the cylinder is considered, are provided with numerous minute perforations 10 26, through which communication is established between the interior of the cylinder 15 and the casing through the open outer sides of the buckets.

The casing is provided near its center with 15 partition-rims 27, which extend to the periphery of the revolving cylinder. The central portion of the latter, located between the said partition rims or plates is provided with a circumferential slot 28, which is formed by 20 removing portions of the segmental plates or sections 21. The two ends of the casing, which are designated, respectively, by 29 and 30, are thus separated from each other, except in so far as communication between them may be 25 had through the hollow cylinder. The central portion of the casing is provided with an upward extension 31, in the upper end of which is journaled a pulley 32. A belt or band 33, made of flexible sheet metal, passes over 30 the said pulley and around the slotted central portion of the cylinder, said belt serving to cover the said slot in that portion of the cylinder which is temporarily the lower portion. Inlet-pipes 34 and 35 are attached to 35 the casing and communicate, respectively, with the compartments 29 and 30 of the latter, and an outlet-pipe 36 is attached to one side of the upward extension 31 of the casing.

In operation the material which is to be 40 treated is fed into the cylinder through the pipe 10 at one end of the same. Through the pipe 34 a blast of hot air is directed into the section 29 of the casing, and a blast of cold air is similarly directed through the pipe 35 45 into the section 30 of the casing, the respective blasts serving to diffuse and distribute the hot and cold air, respectively, through the entire space of each of the sections of the casing, entirely surrounding the ends or sections of the cylinder contained therein. The casing of an exhaust-fan is suitably connected 50 with the outlet-pipe 36. A rotary motion in the direction indicated by the arrow in Fig. 4 of the drawings is now communicated to the 55 revolving cylinder, the contents of which will thus be kept continually agitated by means of the buckets 22, the flat perforated sides of which serve to lift and elevate the said contents of the cylinder and to discharge it back 60 into the same when a certain elevation has been reached. The hot air which is being forced into the section 29 of the casing will pass through the open outer sides of the buckets and through the perforated sides of 65 said buckets into the cylinder, it being thus forced through the contents of the cylinder, vaporizing the excessive moisture of said

contents. In like manner the cold air which is being forced into the section 30 of the casing is caused to pass through the perforated buckets and into the cylinder, thereby cooling the contents of the latter. Both the hot and the cold air, as well as the vaporized moisture, are drawn by the suction created through the escape-pipe 36 to the center of the cylinder, and thence through the slots 28 into the upward extension 31 of the casing, and out through the discharge-pipe 36. The endless belt 33, as will be seen, serves to cover the slot 28 in that part of the cylinder which is temporarily the lower part. The contents of the cylinder are thus prevented from escaping through the said slot. At the same time said belt offers no obstruction to the passage of the air through the upper portion of said slot and to the escape-pipe 36. Owing to the inclined or tilted position of the cylinder, the material which is being operated upon will travel slowly and gradually from the feed end to the discharge end of the machine, where it escapes through the opening covered by the hood 19. During its passage through the machine the material is subjected, in the manner described, first to the action of the hot air and next to the action of the cold air. It is thus deprived of its excessive moisture, and gradually cooled in such a manner as to prevent it from clogging or matting either during its passage through the machine or after being discharged from the latter.

The construction of the machine is simple and inexpensive, and it may be operated more efficiently and with better results than machines for similar purposes that have heretofore been in use.

Having thus described my invention, what I claim is—

1. The herein-described revoluble cylinder, composed of a series of longitudinal and separate plates connected by means of the inwardly-projecting and perforated buckets secured interiorly to said plates, substantially as set forth.

2. The combination, with a casing having separate compartments for the admission of hot and cold air, of the revolving cylinder arranged within said casing and provided with the interiorly-arranged buckets having perforated sides and open bases, substantially as set forth.

3. The combination, with a casing having separate compartments for the admission of hot and cold air and provided with a centrally-located upward extension having an exit-pipe, of the revolving cylinder arranged longitudinally within the said casing and having the interiorly-located buckets with perforated sides and open bases, substantially as set forth.

4. The combination of the casing having separate compartments for the admission of hot and cold air and having a central upward extension provided with an escape-pipe, the

revolving cylinder arranged within said casing and composed of segmental plates connected by interiorly-located buckets having flat perforated sides and open bases, said cylinder being provided with a central circumferential slot, a guide-pulley journaled in the upward extension of the casing, and an endless belt passing over said pulley and under the circumferential slotted portion of the cylinder, substantially as set forth.

5. In a machine for manipulating tobacco and like material, the combination, with a casing having separate end compartments with inlets respectively for hot and cold water and a central or intermediate compartment having an outlet, of a cylinder mounted revolvably in the said casing and having interiorly-located longitudinal buckets and provided with openings whereby the interior of said 15 cylinder shall be caused to communicate with each of the compartments of the casing, substantially as set forth.

6. The combination of a casing having separate compartments for the admission of hot and cold air and an intermediate compartment provided with an outlet, a slightly inclined or tilted cylinder mounted revolvably in said casing and having interiorly-arranged buckets and provided with openings communicating with each of the compartments of the casing, a feed-pipe extending through a central opening in the closed feed end of the cylinder, and a discharge-opening in the opposite end of the casing, substantially as set forth.

35 7. The combination, with the revoluble cylinder composed of segmental plates connected by interiorly-arranged buckets having flat perforated sides and open bases, said cylinder being provided with a central circumfer-

ential slot, of a casing having separate compartments for the admission of hot and cold air and provided with a central or intermediate compartment having an outlet, a guide-pulley journaled in said central or intermediate compartment, and an endless belt passing over said guide-pulley and under the central circumferentially-slotted portion of the cylinder, substantially as set forth. 45

8. The combination of a casing, partitions therein, a revoluble cylinder having openings therein and provided with inwardly-extending perforated buckets and with a circumferential slot registering with the middle compartment in the casing, inlet-pipes at the end 50 compartments of the casing, an upward extension of the middle compartment having an exit-pipe, a guide-pulley, and an endless band passing over the latter and under the circumferentially-slotted portion of the cylinder, substantially as set forth. 55

9. An organized machine for treating fine-cut tobacco and like material, comprising a casing provided with means for the admission simultaneously of hot and cold air in opposite ends thereof, a revoluble cylinder having openings therein, and means for exhausting from a central portion of the casing the said hot and cold air, together with the vaporized moisture of the material that is being 60 operated upon, substantially as and for the purpose set forth. 65

In testimony that I claim the foregoing as my own I have hereto affixed my signature in presence of two witnesses.
